UNITED STATES PATENT OFFICE.

REUBEN B. BENJAMIN, OF CHICAGO, ILLINOIS.

PULL-SWITCH SOCKET FOR ELECTRIC LAMPS.

1,184,063.

Specification of Letters Patent.

Patented May 23, 1916.

Application filed October 6, 1913. Serial No. 793,532.

To all whom it may concern:

Be it known that I, REUBEN B. BENJAMIN, a citizen of the United States, residing at Chicago, in the county of Cook and State of Illinois, have invented new and useful Improvements in Pull-Switch Sockets for Electric Lamps, of which the following is a full, clear, concise, and exact description, reference being had to the accompanying drawing, forming a part of this specification.

My invention relates to improvements in pull switch sockets for electric lamps, that is to say, sockets of the type in which the switch is opened or closed, to extinguish or light the lamp, by a cord, chain or the like. As sockets of this class are usually constructed, if a shade is used, the operating chain or cord extends over the edge of the shade and hangs down from this point to where it can be reached by a person desiring to manipulate the switch. When the chain or cord is pulled the fixture is jarred or caused to vibrate to such an extent as to endanger the filament of the lamp, especially if the latter be a tungsten or other metallic filament lamp, which, as is well known, are not adapted to rough usage. This jarring is due to the fact that the pull occurs at a point considerably removed from the axis of the socket and to the engagement of the chain or cord with the edge of the shade.

It is the principal object of my invention to remedy the above defects and to provide a pull switch socket in which the possibility of the fixture being jarred or caused to vibrate is reduced to a minimum.

It is a further object of my invention to provide a convenient and simple construction of pull switch socket in which the switch operating member is disposed between the lamp and any shade which may extend from the socket.

In the accompanying drawing and the following description I have disclosed one preferred embodiment of my invention, but I wish it understood that changes may be made in the form, construction, and arrangement of the parts without exceeding the scope of the appended claims.

In the drawings: Figure 1 is a side elevation of a pull switch socket constructed in accordance with my invention, a part of the same being broken away to disclose the connection and arrangement of the switch op-

erating member; and Fig. 2 is a front view of the same.

The socket comprises a tubular casing shell 3 formed of sheet metal or other suitable material, and lined with fiber or other insulating material. In the upper part of the casing 3 is arranged a switch mechanism of any suitable type which is adapted to be operated by means of a cord or chain. The casing 3 is also adapted to contain the usual screw-threaded lamp engaging contact shell, and is provided with an annular bead 4 which serves as a support for the holder 5 of a shade 6. A cap 7 is provided to fit over the top of the casing 3 and is held in place by the spring retaining members 8, which are formed in the casing 3. The cap 7 is provided with a boss 9 to which is secured a bushing 10, screw-threaded on the interior for engaging the conduit or feed wires. The shell 3 has an enlarged portion to contain the insulating base for the contacts, said enlarged portion forming, on the casing 3, a shoulder 11. In the lower face of the shoulder 11 is a downwardly directed aperture 12. In this aperture is secured an elongated hollow rivet 13 through which the switch operating member is adapted to pass. The switch operating member is a chain 14 composed of thin, flat links. If so desired, it may have an extension 15 of any ornamental form.

It will be noted that, by virtue of the construction and arrangement of my socket shell and chain, the chain 14 lies close to the side of the casing 3, so that, being of attenuated cross section, it can pass, without any appreciable change in its direction, through the space existing between the shade 6 and the lamp. In pull switch sockets as usually constructed, the operating member, usually a ball chain, emerges from the casing above the shade and hangs down the outside and over the edge thereof. Such sockets are open to the important objection that when the switch is operated considerable vibration of the lamp is caused, and the life of the lamp filament consequently shortened. Attempts have been made to avoid this objection; but the resulting constructions have been cumbersome and unsightly and not entirely successful. My invention obviates this objection in a very simple manner and in a way which increases the attractiveness of appearance of the fixture. The

chain 14 is operated in a line which is parallel with, and close to, the axis of the socket, so that the vibration resulting from the operation of the switch is reduced to 5 such an extent as to be negligible.

Having thus described my invention, what I claim as new and desire to secure by Letters Patent is—

1. A lamp socket including a casing having the lower portion thereof reduced to 10 form a shoulder and having a guide opening formed in said shoulder, a pull switch contained in said casing, and an operating member for said switch passing through 15 said guide opening, for the purposes set forth.

2. In combination, a lamp socket including a casing having the lower portion thereof reduced to form a shoulder and having a 20 guide opening formed in said shoulder, a lamp contained in said socket, a shade associated with said socket, a pull switch contained in said socket, and an operating member for said switch passing through 25 said guide opening, said operating member having a portion thereof formed of attenuated cross section and passing through the space between said shade and said lamp.

3. In combination, a lamp socket, a shade 30 holder carried thereby having an opening therein affording a passage from the outside of the socket to the space between the shade and lamp, a switch associated with said socket, and a switch operating member 35 connected with said switch and passing

through said opening to a position in which it will lie between the lamp and shade.

4. In combination, a lamp socket, a shade carried thereby, a switch associated with said socket, a casing surrounding said socket 40 and switch and having an opening in the side thereof, and switch operating means connected with said switch and passing through said opening and through the upper part of said shade to a position between 45 said shade and the lamp.

5. In combination, a lamp socket, a shade holder carried thereby having an opening therein, a switch associated with said socket, a casing surrounding said switch and socket 50 having an opening in its side, and switch operating means connected with said switch and passing through both of said openings to a position in which it will lie between the lamp and shade. 55

6. A lamp socket including a casing having the lower portion thereof reduced to form a shoulder and having an opening formed in said shoulder, a tubular guide member secured in said opening, a pull switch contained in said casing, and an operating member for said switch passing through said tubular member for the purpose set forth. 60

In witness whereof, I have hereunto subscribed my name in the presence of two witnesses. 65
